UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

ASSEMBLING AND LASTING MACHINE.

Application filed January 10, 1919, Serial No. 270,495. Renewed March 24, 1925.

This invention relates to machines for use in the manufacture of boots and shoes for working uppers over lasts. The invention is herein illustrated as embodied in a machine designed for assembling shoe parts upon their lasts and for lasting the rear end and heel seat portions of shoe uppers. In the manufacture of some kinds of shoes such, for example, as one type of rubber soled 10 shoes commonly known as sneakers, it is a usual practice to secure the upper in conformity to the contour of the last by causing the margin of the upper to adhere to the insole, for example, by the use of cement. 15 An object of this invention is to provide an improved machine adapted for use in the manufacture of shoes of this type for working an upper over its last and causing it to be secured thereto, but it will be understood 20 that the invention is not limited with respect to utility to the manufacture of this particular kind of shoe nor to the manufacture of shoes in which the soles or other parts are made of rubber. Moreover, in its 25 broader aspects the invention is not restricted with respect to the portion of the shoe upon which the operations may be performed.

Rubber soled shoes of the kind above mentioned are usually made with a comparatively thin and flexible innersole which is shaped from a rubber compound and which is not vulcanized until after the lasting operation on the shoe. During the operation 30 of conforming the upper to the last, the innersole is in a comparatively soft and yielding condition, and for this reason it is necessary to avoid any action upon the shoe materials such as would tend to wrinkle 35 the innersole or to displace it from the edge of the last. Because of this condition the operation of lasting shoes of this kind has very largely been performed by hand. This invention provides a machine so constructed 40 as to perform its operation upon the shoe without danger of displacement of the innersole relatively to the last, the term innersole being used herein as a generic term to indicate that part of the shoe to which the 45 upper is secured to hold it in conformity to the last irrespective of the type of shoe. 50

A feature of the invention consists in a

novel organization including means for deflecting the margin of an upper extending about the heel end portion of a shoe into a position over the shoe bottom, but out of substantial contact therewith, and means which acts preferably by impact to press the inwardly disposed upper into firm contact with the shoe bottom. As shown herein the deflecting means, frequently hereinafter termed deflectors, for laying the upper over the shoe bottom comprises plates or blades each extending along the side of the shoe end including the corner portion of the shoe end which plates are moved inwardly over the shoe bottom to bend the upper at the edge of the last and dispose it over the shoe bottom but without applying substantial downward pressure upon the upper and without extended movement over the shoe bottom, thus leaving a substantial portion of the upper margin extending inwardly beyond the edge of the plates to be treated by impact. The plates for overlaying the upper may be similar in construction to the lasting wipers of bed lasting machines and may, for the purpose of identification, be referred to as wipers in the specification and claims. It should be borne in mind, however, that the function of these plates, in the organization herein shown, is distinct from that of the usual lasting wipers in that they act, not in the plane of the surface of the innersole to wipe the upper into firm contact with the innersole, but in a plane above the innersole to bend inwardly the upper and dispose or lay the upper in a position over the innersole but without applying substantial pressure to the upper against the innersole. Furthermore, the movement of the plates over the shoe bottom is restricted so as to expose a substantial portion of the overlaid margin to the action of the impacting means to effect adhesion of the upper to the shoe bottom. As shown herein impact members are provided which are preferably carried by the plates and lie just inside their upper engaging edges, the members being actuated, subsequently to the action of the plates in inwardly bending the upper, to force the upper into adhering contact with the shoe bottom.

Another feature of the invention consists

in means acting after the shoe is positioned in the machine to tension the upper at the sides of one end of the shoe toward the other end of the shoe. In the organization 5 herein shown the shoe is held in the machine in position for treatment of the upwardly extending margin of the upper at the heel end of the shoe and the tensioning means are moved forwardly against the opposite 10 sides of the rear end of the shoe to rub the upper forwardly in conjunction with the treatment of the projecting margin.

Another feature of the invention consists in an organization of overlaying means including plates or wipers and a roll acting 15 between the plates for rolling into contact with the innersole the portion of upper lying between the plates. This portion is preferably that at the extreme end of the 20 shoe. The roll, as herein shown, is of substantial diameter and has a relatively narrow upper engaging face.

Another feature of the invention consists in novel means for positioning relatively to 25 the shoe mechanism for laying the upper over the innersole, the construction shown comprising means for locating the roll at a predetermined distance below the shoe bottom before it advances over the shoe bottom. 30 As herein shown the roll is on a resiliently depressed carrier which is held raised and allowed to drop before advance of the roll, and means is provided on the carrier to engage the shoe bottom and limit descent of 35 the roll relatively to the shoe bottom. Preferably the limiting means is adjustable and is provided on its shoe engaging face with anti-friction means to facilitate its advance in contact with the shoe bottom as the carrier and roll are advanced over the shoe bottom.

A further feature of the invention consists in means for determining the plane of action of the deflectors relatively to the shoe bottom, as herein shown, so that they will act in a plane slightly above that of the shoe bottom and will bend inwardly the margin of the upper without forcing it into substantial contact with the upper surface 5 of the innersole. As herein shown the roll which treats the upper at the rear end of the last is employed to determine the plane of action of the deflectors and for this purpose the roll and deflectors are arranged for 10 relative adjustment perpendicularly to the shoe bottom.

Further features of the invention consist in a novel construction of the deflectors and the means for detachably holding them in the 15 machine; in a novel construction of the shoe support; in novel means for positioning the shoe in the machine and in other details of construction and combinations of parts, all of which will appear more fully 20 from the following description when read in

connection with the accompanying drawings and will be pointed out in the appended claims.

In the drawings,

Fig. 1 is a side elevation of the machine, 70 a portion of the base being omitted;

Fig. 2 is a perspective view of the operating parts of the machine shown in Fig. 1;

Fig. 3 is a plan view, partly in section, of the lasting mechanism;

Fig. 4 is a perspective detail of the parts shown in Fig. 3;

Fig. 5 is a perspective detail of the parts shown in Fig. 3;

Fig. 6 is a sectional view, partly in elevation, of the parts of the machine which operate upon the shoe;

Fig. 7 is a view similar to Fig. 6 showing the parts in a different position;

Fig. 8 is a view of the rear portion of 85 the shoe before the operation of the machine has been performed upon it; and

Fig. 9 is a similar view after the operation of the machine.

Referring to Fig. 1 of the drawings, the numeral 2 indicates the column of the machine near the base of which is pivoted a jack support 4 for movement toward and from the machine. Fixed to the support 4 is a jack post 6 in the upper end of which 90 is telescoped a threaded rod 8. The rod 8 is adjusted vertically by a hand nut 10 which is held from vertical movement by a clip 12 attached to the post 6 and engaging an annular groove in the nut 10. To prevent accidental disturbance of the vertical adjustment of the rod 8 in the post a split clamp 14 is provided which is operated by a handle 16. On the upper end of the rod 8 is mounted 95 the shoe jack which comprises a head 18 pinned to the post 8 and having upstanding ears 20 between which is pivoted at 22 a last pin carrier 24 having, as shown, two last pins 26, 28 of different sizes either of which may be moved into operative position by 100 turning the carrier on its pivot 22. Either last pin is movably retained in operative position by an upwardly spring-pressed plunger 30 (Fig. 6) having a flat head 32 to engage suitable flattened faces 34, 35 on the carrier 24. Preferably a projection is provided on the head 32 to engage suitable recesses formed in the faces 34, 35, as is clearly 105 shown in Fig. 6. This construction serves to hold either pin 26 or 28 in operative position but enables the carrier 24 to be turned by the application of force to shift one pin out of operative position and the other into operative position. Extending outwardly 110 from the head 18 is a projection 38 (Fig. 1) which carries a toe rest slide 40. The slide 40 has depending ears 42 between which is mounted at 43 a pinion 44 meshing with teeth 46 formed on the under side of the projection 38. The pinion 44 is turned by a 115

120

125

130

hand wheel 48 to adjust the slide 40 longitudinally of the shoe and the slide is retained in adjusted position by engagement of a suitable spring plunger with a toothed wheel 50 fixed to the pinion 44. A toe rest 52 is mounted for vertical adjustment in the slide 40 and is held in adjusted position by a split clamp 54 operated by a handle 56.

To hold the jack toward the machine during its operation upon the shoe, a hook 60 is pivoted at 62 in the column 2 and arranged to engage a roll 64 mounted on a rearward projection 66 from the jack support 4. The hook 60, when released, is depressed by a spring 67 suitably arranged on its pivot 62 and the face of the hook which engages the roll 64 is cammed to force the jack rearwardly and hold the rear end of the shoe against a V-block 68 secured to the machine head frame 70 (Fig. 2). To raise the hook against its depressing spring 67, a cam 72 is provided on the main shaft 74 of the machine which cam acts on a roll carried by one arm 76 of an angle lever pivoted at 78 to the frame 70. The other arm 80 of the angle lever is pivotally connected by a push rod 82 to a rearward extension 84 of the hook 60. The cam 72 acts to raise the hook at the end of the machine cycle and to release it when the machine is started.

The hook 60 is utilized to control the operation of pressing and rubbing members 81, 83 arranged to engage the opposite sides of the rear end of a shoe positioned on the jack and held by the hook against the V-block 68 (Fig. 2). The members 81, 83 are mounted respectively on arms 85, 87 fixed to the upper ends of upright rods 88, 90 mounted to turn in bearings 92, 94 carried by laterally extending arms of a slide 96 mounted in the head frame 70 for movement longitudinally of the shoe. The rods 88, 90 are turned, when permitted to do so, to force the members 81, 83 against the shoe by torsion springs 98, 100, the upper ends of the springs being held respectively by the bearings 92, 94, and the lower ends of the springs being held in collars 102, 102 fixed to the rods 88, 90. The lower ends of the rods 88, 90 are fixed to heads 104, 106 having universal joint connections 108, 110 to members 112, 114, which have stems telescoped into members 116, 118, and splined therein (Fig. 7) so that rotative movement may be transmitted from the members 116, 118 to the members 112, 114. The members 116, 118 have universal joint connections 120, 122 to members 124, 126 which have reduced portions mounted in bearings 128, 130 formed in a bracket 132 secured to the machine column 2. Below the bearings 128, 130, the members 124, 126 have inwardly directed arms 134, 136 secured thereto which arms are engaged by a arm 138 of an angle lever pivoted at 140 to a downward extension of the bracket 132, the other arm 142

of the lever carrying a roll arranged to be engaged by the hook 60 when it is raised. Raising of the hook 60 operates the lever 138, 142 to effect through the flexible connections described a separation of the rubbing members 81, 83 against the tension of the torsion springs 98, 100, which springs are, of course, released when the hook is depressed to force the members 81, 83 against the shoe. The flexible connection described between the rods 88, 90 and the members 124, 126 is necessitated by the fact that the slide 96 carrying the rods 88, 90 and pressing and rubbing members 81, 83 is moved longitudinally of the shoe to effect a movement of the members 81, 83 in rubbing contact with the rear end of the shoe to tension the upper forwardly of the shoe and ensure proper fitting of the upper to the rear end of the last and tighten the upper at the back seam.

The means for effecting movement of the slide 96 and the rubbing members 81, 83 is illustrated in Figs. 6 and 7, Fig. 6 showing the position of the members 81, 83 when they engage the last, and Fig. 7 showing their position after the slide 96 has been moved forward. Movement of the slide 96 is effected by a lever pivoted at 150 to the head frame 70 and having one arm 152 forked to engage a stud 154 on the slide 96. The other arm 155 of the lever is adjustably pivoted at 151 to a bar 156 (Fig. 1) which extends to the rear of the machine where it is pivoted to a lever 158 fulcrumed at 160 to the head frame 70 and having at its upper end a fork 162 engaging a pin 163 on a forwardly moving slide 164 carrying a roll 166 which engages a path cam 168 on the main shaft 74.

It will be seen that forward movement of the slide 164 effects through the described connections, a forward movement of the rubbing members 81, 83 longitudinally of the shoe. The initial position of the members may be varied by adjustment of the pivot 151 relatively to the bar 156. This is desirable because shoes of different sizes are differently positioned longitudinally in the V-block 68. The members 81, 83 preferably have the construction best disclosed in Fig. 2 where they are shown as comprising blocks 115 having curved shoe engaging faces and angular portions adapted to be seated in V-shaped notches in the inner faces of the arms 85, 87. The blocks preferably have coverings 89 of leather or other suitable friction material. The coverings are held to the blocks 81, 83 by locating the ends of the covering material between the blocks and the arms so that they will be clamped when screws 91 which secure the blocks to the arms are tightened.

Lasting in of the upwardly projecting margin of the upper above the heel seat of the shoe is effected by mechanism mounted on a carrier 170 pivoted at 172 to the slide 130

164 and downwardly spring pressed by a plunger 173 carried by the slide and engaging a ledge 175 in the carrier 170. The carrier is raised against the action of the plunger 173 by a cam 172 acting on a lever 174 pivoted at 176 to the frame 74 and carrying on its forward end a block 177 arranged to engage and raise the carrier 170. When the machine is in stopped position the carrier 170 is raised as shown in Fig. 1. The cam roll 166 is mounted on a block 167 arranged to move horizontally in the slide 164. The block 167 is adjusted by a screw 169 extending to the front of the machine and provided with a hand wheel 171. Adjustment of the block 167 varies the initial and hence the advanced positions of the slide 164 and also those of the carrier 170 and the lasting instrumentalities carried by it.

20 Prior to starting the machine, it is desirable to locate the shoe bottom in a predetermined vertical position. For this purpose a positioning member 180 is provided. The member 180 is pivoted at 182 to the carrier 170 and may be swung downwardly into operative position, as shown in Figs. 1 and 6, and upwardly into an inoperative position, as shown in Figs. 2 and 7, being held in either position by a suitably arranged spring 184. The shoe engaging end of the member 180 may be provided with an adjustable plate 186 to vary the effective length of the member. In adjusting the machine for shoes of a given size, the member 180 is swung down and the hand nut 10 on the jack adjusted until the surface of the bottom of a shoe on the jack will just engage the lower end of the positioning member 180 or the plate 186 thereon. The member is then swung up out of the way and is not used again until it is necessary to adjust the machine for shoes of a different size.

45 After the above described adjustments have been made, the shoe is held pressed against the V-block 68 and a treadle, with which the machine is provided, is depressed to start the machine, the treadle operating a clutch of any suitable type to control rotation of the main shaft 74 by power. A suitable form 50 of clutch for this machine is disclosed and claimed in United States Letters Patent No. 1,026,067, granted May 14, 1912 on application of Orrell Ashton. When the machine starts the cam 72 first releases the hook 60 which operates to hold the jack toward the machine with the rear part of the shoe thereon pressed against the V-block 68. A little later the cam 172 releases the roll on the lever 174 which allows the carrier 170 to be depressed by the plunger 173, causing an anti-friction roll 190 (Fig. 6) to come in contact with the shoe bottom. The roll 190 is arranged for vertical adjustment relatively to the carrier 170 by mounting it on a slide 192 which can be moved up and down by

turning a screw 194 threaded into the carrier 170 and having a thumb head 196. The slide 192 has a forked lug 198 engaging between the flanges formed on the screw 194. One of the flanges is provided with notches co-operating with a spring plunger 200 to prevent accidental turning of the screw. Engagement of the roll 190 with the shoe bottom locates relatively to the plane of the shoe bottom a roll 202 mounted to turn freely on a shaft 204 which is eccentrically journalled in the carrier 170 (Fig. 3), one of the journals being extended outside the carrier (Figs. 1 and 2) and provided with an arm 206 fixed thereto by which it may be turned to vary the vertical position of the roll on the carrier. The end of the arm 206 is provided with a suitable spring pin 207 to engage any one of a series of holes 208 in the outer face of the carrier 170. The edge of the roll 202 is located, by adjusting the roll 190, in a plane somewhat below that of the roll 190 so that the roll 202 will engage the corner of the rear end of the last and ride up over it, thereby laying the upwardly projecting margin of the upper in the region of the back seam into firm engagement with the shoe bottom, as illustrated in Figs. 6 and 7. When the roll 202 approaches the position shown in Fig. 7, it has lifted the carrier 170 somewhat so that the roll 190 no longer contacts with the shoe bottom.

55 The roll 202 constitutes one of the lasting instrumentalities with which the machine is provided and by raising the carrier 170 as it advances toward the position of Fig. 7, to a position determined by the adjustment of the roll 202, it positions other lasting instrumentalities relatively to the shoe bottom for their operation on the remainder of the upper projecting above the heel seat, which operation takes place during the advance of the roll 202 over the shoe bottom toward the position shown in Fig. 7. These other lasting instrumentalities comprise a pair of deflectors 210, 212, shown in detail in Figs. 3 and 4, which are mounted for turning movement on pins 214, 216 mounted in the carrier 170 and are operated by relatively stationary pins 218, 220 arranged in slots 222, 224 formed in portions of the deflectors extending rearwardly of their pivots 214, 216. The pins 218, 220 are carried by a plate 226 (Fig. 4) which is fixed to a block 228 having a rib 230 engaging a groove 232 in the frame 70. The block is adjustably held by a screw 234 passing through a slot in the block and threaded into the frame. The screw is preferably provided with a handle 235 for conveniently loosening the screw for adjustment of the block which varies the time during the advance of the carrier when the closing movement of the deflectors begins. From Fig. 3 it will be seen that the slots 222, 224 have

parallel portions and converging portions so that a certain amount of movement of the carrier 170 is permitted before the deflectors are closed against the upper. The block 228 is so adjusted that the deflectors will begin to close after the roll 202 has raised the carrier by its advance over the rear end of the shoe. The deflectors are then located by adjustment of the eccentric axis of the roll 202.

10 in a plane slightly above the plane of the bottom of the innersole, and as they close they act to bend or deflect inwardly the up-standing margin of the upper about the entire heel seat except the part at the rear end already treated by the roll 202.

The advance of the deflectors over the shoe bottom is not great but is sufficient to dispose the margin of the upper beneath a pair of pounders 240, 242 carried one by each 20 deflector and operated to force the upper by impact against the bottom of the innersole. The pounders 240, 242 are coextensive with the acting edges of the deflectors and correspond in outer edge contour to the inner 25 edge contour of the deflectors. The pounders 240, 242 are preferably carried by the deflectors. The pounder 240 has an arm 241 extending across the deflector 210 and pivoted to ears 244 on the deflector. The other 30 pounder 242 is similarly mounted on the deflector 212. The pounders are operated at the proper time in the cycle of the machine by a driver bar 246 mounted for vertical lengthwise movement in the carrier 170 and 35 having fixed to its lower end (Fig. 6) a member 247 on which is a T-head or cross bar 248 (Fig. 2) arranged to strike, in its descent, upstanding lugs 250 formed one on each of the pounders 240, 242. The blow delivered by the driver bar upon the pounders 40 causes them to force the margin of the upper, which has been inwardly deflected beneath them by the deflectors 210, 212, against the innersole and to cause firm adhesion between the cemented engaging surfaces of the 45 upper and innersole.

The necessary impact of the driver bar T-head 248 upon the pounders is effected by a lever 252 overlying the bar 246 at one end and fixed to a pivot shaft 254 at the other. 50 On the shaft 254 is a torsion spring 256 arranged to force downwardly the opposite end of the lever 252. Between its ends the lever 252 carries a roll 255 acted upon by a cam 258 on the shaft 74 to raise and release the lever 252. The bar 246 has a head 260 to limit its downward movement which head is connected to the lever 252 by springs 262 (Fig. 2) to effect raising of the bar 60 when the lever is raised.

The deflectors 210, 212 are arranged to be easily released for removal from the machine so that other deflectors of different shape may be inserted for use on a different 65 class of work. For this purpose the pivot

pins 214, 216 of the deflectors engage open slots 270 (Fig. 4) which slots, at their inner ends, have recesses 272 to receive heads 274 on the pins 214, 216. When the heads 274 are positioned in the recesses 272, the deflectors can only turn on the pins and cannot be withdrawn. When the pins are depressed, however, to free the heads from the recesses, the slots 270 permit the deflectors to be withdrawn bodily out of the machine, 70 the slots engaged by the operating pins being open at their rear end to permit this. In order that the deflectors 210, 212 may conveniently be withdrawn both at the same time, the pins 214, 216 are connected together so that they can both be released by a finger lever. This is effected by the construction shown in detail in Fig. 5. The pins 214, 216 have teeth formed therein and are engaged respectively by the ends of arms 75 276, 278 which ends have teeth engaging the teeth on the pins. The arms 276, 278 are clamped by screws 280 to a rock shaft 282 journaled in a portion of the slide 170. The arm 276 has an upstanding arm 284 by 80 movement of which the pins 214, 216 may both be depressed to release the deflectors 210, 212. The arm 284 is locked to hold the heads 274 in the recesses 272 by a spring pin 286 arranged to engage a hole in a relatively 85 stationary part of the carrier 170. By reference to Figs. 2 and 3, it will be seen that the inner ends of the deflectors 210, 212 have notches 290 which engage a ledge 292 formed on a member 294 secured to the carrier 170. 90 The edge of the ledge is formed with two curved portions one concentric with the pin 214, and the other concentric with the pin 216. This construction, while permitting relative closing movement of the deflectors, 95 guides them in their closing movement and prevents longitudinal tipping movement of them on their pivot pins 214, 216.

Having thus described my invention, what I claim as new and desire to secure by Letters Patent of the United States is:

1. A machine of the class described having, in combination, means for deflecting the upwardly projecting margin of an upper extending about the heel seat of a shoe into a position inclined over the shoe bottom but out of substantial contact therewith, and means acting while the deflecting means remains in deflecting position to press the portion of the inwardly disposed upper lying 115 inside the deflecting means relatively to the shoe bottom into contact with the shoe bottom.

2. In a machine of the class described, the combination of actuating means, means for bending an upper over the last edge at the two sides of the end portion of a last, and means carried by the bending over means arranged for actuation against the portion 120 of upper extending beyond the bending over. 130

means to force the upper into contact with the shoe bottom.

3. A machine for working an upper over a last and causing it to be secured by adhesion to an innersole, having, in combination, means for bending the margin of the upper inward over the innersole, and means carried by the bending means and operated to engage the inwardly bent margin of the upper and press it into position to adhere to the innersole.

4. A machine of the class described having, in combination with actuating means, a tool for disposing a portion of the upper of a shoe inwardly over the shoe bottom, and a second tool mounted on the first tool acting to beat against the shoe bottom the portion of upper treated by the first mentioned tool.

5. A machine for working an upper over a last and causing it to be secured by adhesion to an innersole, having, in combination, means for deflecting the margin of the upper inwardly over the innersole out of substantial contact with the innersole, pressers mounted upon the deflecting means to engage the inwardly deflected margin of the upper beyond the bending means, and means acting in timed relation to the bending means to force the pressers against the margin of the upper and cause it to adhere to the innersole.

6. A machine for working an upper over a last and causing it to be secured by adhesion to an innersole, having, in combination, means for deflecting the margin of the upper inwardly over the innersole out of substantial contact with the innersole, pressers pivoted to the deflecting means and normally out of contact with the upper, and means acting in timed relation to the bending means to operate the pressers by impact and cause them to force the upper into adhering contact with the innersole.

7. A machine for working an upper over a last into position to be secured, having, in combination, means for deflecting the margin of the upper inwardly over the innersole out of substantial contact with the innersole, pounders mounted upon the deflecting means to engage the inwardly deflected margin of the upper beyond the deflecting means, and separate spring actuated means arranged and operated to engage the pounders by impact and cause the upper to be pounded against the innersole.

8. A machine for working an upper over a last and causing it to be secured by adhesion to an innersole, having, in combination, means for deflecting the margin of the upper inwardly over the innersole out of substantial contact with the innersole, pounders mounted upon the deflecting means to engage the inwardly deflected margin of the upper beyond the bending means and

pound it against the shoe bottom, and means acting in timed relation to the pounding means to force the upper at the side of the shoe against the last.

9. A machine of the class described having, in combination with actuating means, a pair of curved deflectors for disposing the upper of a shoe inwardly of the shoe bottom at opposite sides thereof, and a pair of upper impacting tools arranged inside the deflectors and having the same curved contour as the deflectors at their adjacent edges.

10. A machine of the class described having, in combination with actuating means, a pair of curved deflectors for disposing the upper of a shoe inwardly of the shoe bottom at opposite sides thereof, and a pair of tools arranged inside the deflectors and having the same curved contour as the deflectors at their adjacent edges, said actuating means being constructed and arranged to operate the deflectors and tools successively in the same cycle.

11. In a machine of the class described, the combination of actuating means, means having the contour of the last edge for bending an upper over the last edge at the two sides of the end portion of a last, and separate means corresponding in contour to the bending means lengthwise of the shoe and acting inside of said means relatively to the shoe bottom to beat the bent over portions of the upper into contact with the shoe bottom.

12. A machine for working an upper over a last and causing it to be secured by adhesion to an innersole, having, in combination, means for bending the margin of the upper at the corners and sides of a heel seat inward over the innersole, and means corresponding in contour to the bending means and operated to engage the inwardly bent margin of the upper and press it into position to adhere to the innersole.

13. A machine for working an upper over a last and causing it to be secured by adhesion to an innersole, having, in combination, means for deflecting the margin of the upper inwardly about the periphery of the heel seat of a shoe over the innersole out of substantial contact therewith, pressers corresponding in outer contour to the inner contour of the deflecting means and mounted upon the deflecting means to engage the inwardly deflected margin of the upper beyond the deflecting means, and means acting to force the pressers against the margin of the upper and cause it to adhere to the innersole.

14. In a machine for lasting the rear end portion of a shoe, the combination of means for deflecting the upper over the bottom of the innersole, means for beating the upper against the innersole, and means engaging the sides of the shoe and having a movement forwardly of the last in timed relation to the upper overlaying means.

15. A machine for working an upper over a last, having, in combination, means for supporting a shoe in predetermined position, means arranged for movement after the shoe is positioned to engage the side portions of one end of the shoe and acting to tension the upper toward the other end of the shoe, and means for working the upstanding margin of the upper at the first mentioned end of the shoe into contact with the innersole. 75
16. A machine for working an upper over a last, having, in combination, means for supporting a shoe, means arranged for movement to engage the side portions of one end of the shoe, power means for moving the side engaging means to tension the upper toward the other end of the shoe, and means for working the upstanding margin of the upper at the first mentioned end of the shoe into contact with the innersole. 80
17. In a machine for lasting the rear end portion of a shoe, the combination of overlaying means for disposing the upper over the bottom of the innersole, means for beating the upper against the innersole, and means acting in time relation with the overlaying means for tensioning the upper toward the forward end of the last. 85
18. A machine for working an upper over a last and causing it to be secured by adhesion to an innersole, having, in combination, means for tensioning the sides of the upper at one end of the last toward the opposite end of the last, and means acting in time relation to the tensioning means for working the upper margin at the first mentioned end of the last into position to adhere to the innersole. 90
19. A machine for assembling a shoe upper upon its last, having, in combination, means for tensioning the sides of the upper at the heel end toward the toe of the shoe, and means acting in time relation to the tensioning means for working the upper at the rear end of the shoe into contact with the shoe bottom. 105
20. A machine for working an upper over a last, having, in combination, means for supporting a shoe in predetermined position, means movable after the shoe is positioned to engage the side portions of the rear end of the shoe, means for moving said engaging means to tension the upper toward the toe end of the shoe, and means for working the upstanding margin of the upper at the rear end of the shoe into contact with the inner-sole. 110
21. In a machine for assembling uppers on lasts, the combination of means movable relatively to the last to tension the upper forwardly, means for directing the upper inwardly around the heel seat, and means for beating the upper against the heel seat. 115
22. In a machine for assembling uppers on lasts, the combination of means for rubbing the sides of the upper toward the toe, upper directing blades arranged about the heel seat 120
- on lasts, the combination of means for rubbing the sides of the upper toward the toe of the shoe, means for directing the upper inwardly around the heel seat, and means for forcing the upper against the heel seat. 125
23. In a machine for assembling and lasting the end of a shoe, the combination of power operated means for lasting in the margin of the upper about the heel end of a shoe, and means operated relatively to the shoe in predetermined time relation to the lasting means to rub forwardly the side portions of the upper overlying the heel stiffener. 130
24. In a machine for assembling and lasting the end of a shoe, the combination of power operated means for lasting in the margin of the upper about the heel end of a shoe, and means operatively connected to said lasting means to move relatively to the shoe prior to operation of the lasting means and to rub forwardly the portions of the upper at the sides of the rear end of the shoe. 135
25. In a machine for lasting the rear end portion of a shoe, the combination of overlaying means for disposing the upper over the bottom of the innersole, means for beating the upper against the innersole, and means acting in timed relation to the overlaying means to rub the side portions of the upper longitudinally of the last. 140
26. In a machine for lasting the rear end portion of a shoe, the combination of overlaying means for laying the upper over the bottom of the innersole, and means for engaging the sides of the shoe having a movement forwardly of the shoe in rubbing contact therewith and in timed relation to the action of the upper overlaying means. 145
27. A machine for assembling a shoe upper upon its last, having, in combination, means for rubbing the sides of the upper at the heel end toward the toe end of the last, and power operated means acting after the rubbing means for laying the upper margin at the rear end of the heel into contact with the shoe bottom. 150
28. A machine for conforming a shoe upper to one end of its last, having in combination, a last support movable into and out of operative relation to the machine, means for holding the shoe in the machine, means for rubbing the upper toward the end of the last opposite to that treated by the machine, and means operating in time relation to the rubbing means for laying the upper margin adjacent to the rubbed portion into engagement with the shoe bottom. 155
29. In a machine for assembling shoe uppers upon their lasts, the combination of means for locating a shoe and last in predetermined position, means for rubbing the sides of the upper toward the toe, upper directing blades arranged about the heel seat 160

having their edges conforming to the shape of the curve of the last, means for moving the blades inwardly out of rubbing contact with the heel seat, and means arranged along the inner edge of the blades and operating by impact to beat the upper against the heel seat.

30. In a machine for assembling and lasting the end of a shoe, the combination of a roll acting to lay the upwardly projecting margin of the upper at the end of the shoe into contact with the shoe bottom, means for bending in the side and corner portions of the upper margin, and means for beating said side and corner portions against the shoe bottom.

31. In a machine of the class described, a roll of substantial diameter constructed and arranged to move in a predetermined path longitudinally of the shoe to act at the rear end of a shoe to lay the upstanding margin of the upper into contact with the innersole, and means for varying the vertical position of the roll relatively to the plane of the innersole.

32. In a machine of the class described, a roll of substantial diameter constructed and arranged to act at the center of the rear end of a shoe to lay the upstanding margin of the upper into contact with the innersole, and adjustable means engaging the shoe bottom for varying the position of the roll relatively to the plane of the shoe bottom.

33. A machine for working an upper over a last and causing it to be secured by adhesion to an innersole, having, in combination, a pair of plates pivotally located one at each side of the heel seat, means to operate the plates for bending inwardly the margin of the upper at the sides and corner portions of the end of a shoe, and a roll located between said plates to force a portion of the margin at the end of the shoe against the innersole.

34. A machine for working an upper over a last and causing it to be secured by adhesion to an innersole, having, in combination, means for bending inwardly the margin of the upper at the sides and corner portions of the end of a shoe, means acting in conjunction with the bending means for causing the portions of the margin treated by the bending means to adhere to the innersole, and a roll acting at the end of the shoe to lay another portion of the margin into adhering contact with the innersole.

35. A machine for working an upper over a last, having, in combination, means for supporting a shoe, a carrier movable longitudinally of the shoe, means for lifting the carrier before the machine stops and releasing the carrier after the machine starts, positioning means mounted on the carrier and arranged to engage the shoe bottom when the carrier is released, and a roll mounted on

the carrier and located by the positioning means in a plane below the plane of the last bottom and adapted as the carrier advances to engage and ride over the edge of the last.

36. A machine for working an upper over a last and causing it to be secured by adhesion to an innersole, having, in combination, wiping means at each side of the heel seat for bending inwardly the margin of the upper at the sides and corner portions of the heel end of a shoe, a roll located between said wiping means to force a portion of the margin at the end of the shoe against the innersole, and means for varying the position of the roll relatively to the wiping means.

37. In a machine for assembling shoe uppers upon their lasts, the combination of upper directing blades at opposite sides of the heel seat having edges conforming to the curve of a last, means acting along the inner edge of the blades for forming the upper by impact against the heel seat, and a roll acting upon the upper between the blades.

38. In a machine for assembling shoe uppers upon their lasts, the combination of upper directing blades at opposite sides of the heel seat having edges conforming to the curve of a last, a roll arranged to engage the last and lift the blades into position to do their work, and means acting along the inner edge of the directing blades for treating the upper by impact against the heel seat.

39. In a machine of the class described, the combination of actuating means, means for bending an upper over the last edge at the two sides of the end portion of a last, means acting prior to the bending means to locate the bending means relatively to the last bottom, and means for beating the bent over portions of the upper which lie inside the bending means into contact with the shoe bottom while still held by the bending means.

40. In a machine of the class described, the combination of actuating means, means for bending an upper over the innersole at the two sides of the end portion of a shoe, means for positioning the bending means a predetermined distance above the innersole, and separate means acting later in the same cycle of the machine and inside the bending over means to beat the bent over portions of the upper into contact with the innersole.

41. A machine for working an upper over a last, having, in combination, means for supporting a shoe in predetermined position, a yieldingly depressed carrier movable longitudinally of the shoe, means on the carrier for deflecting inwardly the upstanding margin of the shoe upper, and a roll on the carrier arranged below the plane of the shoe bottom and adapted to engage the edge of the shoe during the advance of the carrier and to lift the carrier to position the de-

flecting means in the proper plane relatively to the plane of the innersole.

42. A machine for working an upper over a last and causing it to be secured by adhesion to an innersole, having, in combination, 5 a roll acting at the end of the shoe to lay a portion of the margin into adhering contact with the innersole, and means positioned as to their plane of action by said 10 roll for bending inwardly the margin of the upper at the sides and corner portions of the end of the shoe and causing the upper to adhere to the innersole.

43. A machine for working an upper over 15 a last, having, in combination, means for supporting a shoe, a carrier movable longitudinally of the shoe, means on the carrier for deflecting inwardly the upstanding margin of the shoe upper, and a roll on the carrier 20 arranged below the plane of the shoe bottom and adapted to engage the edge of the shoe during the advance of the carrier and to lift the carrier to position the deflecting means in the proper plane relatively 25 to the plane of the innersole to do their work.

44. A machine for working an upper over a last, having, in combination, means for supporting a shoe, a carrier movable longitudinally of the shoe, means for lifting the carrier before the machine stops and releasing the carrier after the machine starts, 30 means mounted on the carrier and arranged to engage the shoe bottom when the carrier 35 is released to locate the carrier relatively to the shoe bottom, a roll mounted on the carrier and located by the bottom engaging means in a plane below the plane of the last bottom and adapted as the carrier advances 40 to engage and be lifted by the edge of the last, and means on the carrier which is positioned by said roll to bend the margin of the upper over the shoe bottom.

45. A machine for working an upper over 45 a last and causing it to be secured by adhesion to an innersole, having, in combination, a pair of plates for deflecting the margin of the upper inwardly over the innersole out of substantial contact with the innersole, 50 means located between the plates to lay a portion of the upper over the last and acting to determine the plane of action of said plates, pressers pivoted to the plates and normally out of contact with the upper, and 55 means acting in timed relation to the plates to operate the pressers by impact and cause them to force the upper into adhering contact with the innersole.

46. A machine for working an upper over 60 a last and causing it to be secured by adhesion to an innersole, having, in combination, means for bending inwardly the margin of the upper at the sides and corner portions of the end of a shoe; and a roll located be- 65 tween said bending means and in a plane

below the bending means to force a portion of the margin at the end of the shoe against the innersole and acting to lift the bending means into position to perform their function.

47. A machine for working an upper over a last and causing it to be secured by adhesion to an innersole, having, in combination, 70 a roll acting at the end of the shoe to lay a portion of the margin of the upper into adhering contact with the innersole, means for bending inwardly the margin of the upper at the sides and corner portions of the end of a shoe and positioned by said roll so to bend the upper without substantial pressure on the innersole, and means acting in conjunction with the bending means for causing the portions of the margin treated by the bending means to adhere to the innersole.

48. A machine for working an upper over a last, having, in combination, means for supporting a shoe in predetermined position, a yieldingly depressed carrier normally upheld and constructed and arranged to be released and moved longitudinally of the shoe upon operation of the machine, a roll on the carrier arranged below the plane of the shoe bottom and adapted to engage the edge of the shoe during the advance of the carrier and to lift the carrier, and means on the carrier for deflecting inwardly the upstanding margin of the shoe upper and positioned in the proper plane relatively to the plane of the innersole by lifting of the carrier.

49. A machine for working an upper over a last, having, in combination, means for supporting a shoe in predetermined position, a yieldingly depressed carrier movable longitudinally of the shoe, means for lifting the carrier before the machine stops and releasing the carrier after the machine starts, 95 positioning means mounted on the carrier and arranged to engage the shoe bottom when the carrier is released to determine the 100 plane of advance of the carrier, a roll mounted on the carrier and located by the positioning means in a plane below the plane of the last bottom and adapted as the carrier advances to engage the last and ride up over the edge of the last thereby lifting the carrier, and lasting means mounted on the carrier and positioned by lifting of the carrier 115 for lasting the upper margin over the shoe bottom.

50. In a machine of the class described, the combination of means for working an upper over the last bottom, an adjustable support for the last, a stop pivoted to the machine frame over the shoe and arranged to be swung in a vertical plane longitudinally of the shoe into and out of position to engage the shoe bottom to indicate the proper adjustment of the support relatively to the over-working means, and a spring 125 130

arranged to hold the stop either in operative or inoperative position.

51. A machine for working an upper over a last and causing it to be secured by adhesions to an innersole, having, in combination, means for positioning a shoe, means for deflecting the margin of the upper inwardly over the innersole, means for moving the deflecting means bodily longitudinally of the innersole, means for causing the deflecting means to move inwardly transversely of the shoe, and means for varying the transverse movement relatively to the shoe without affecting the longitudinal movement.

52. In a lasting machine, the combination of a single pair of end embracing wipers arranged for closing movement over a shoe bottom, separate pivots for the wipers located longitudinally of the shoe a substantial distance outwardly beyond the end of the shoe, said wipers having slotted extensions beyond said pivots, and means acting in said slots to close the wipers.

53. In a lasting machine, the combination of end embracing wipers arranged for closing movement over a shoe bottom, separate pins on which the wipers are pivoted, and means for simultaneously moving the pins to release the members.

54. In a lasting machine, the combination of upper engaging members arranged for closing movement over a shoe bottom, and separate pivots for the members, said members having open slots with recesses at their inner ends, pivot pins arranged to engage the slots and having heads to engage the recesses, and means to disengage the heads from the recesses to permit removal of the members.

55. In a lasting machine, the combination of upper engaging members arranged for closing movement over a shoe bottom, separate pivots for the members, said members having open slots with recesses at their inner ends, pivot pins arranged to engage the slots and having heads to engage the recesses, and means for simultaneously moving the pins longitudinally to remove their heads from the recesses and permit removal of the members.

56. In a lasting machine, the combination of pivoted upper engaging members arranged for closing movement over the shoe bottom, means for moving the members longitudinally of the shoe, said members having surfaces inclined to the direction of longitudinal movement and located rearwardly of their pivots, and relatively stationary means engaging the surfaces for causing the closing movement of the members as they are moved longitudinally.

57. In a machine for rubber shoe work, the combination of means for working the margin of an upper over the sole, said means being constructed and arranged to be re-

moved and exchanged for other similar means designed for a different size of shoe, a shoe support, a plurality of last pins of different sizes on the support, and means constructed and arranged to permit movement of one pin out of operative position and another pin of a different size into operative position to adapt the machine for lasting the size of shoe for which the overworking means in use at the time is designed. 75

58. In a machine of the class described, the combination with shoe positioning means, of a device mounted for movement inwardly over the bottom of the shoe to lay the margin of the upper over the insole, and means movable inwardly over the shoe with said overlaying device for determining by engagement with the insole the position of said device relatively to the plane of the shoe bottom in its operative inward movement over the shoe. 80

59. In a machine of the class described, the combination with shoe positioning means, of end embracing wipers mounted for advancing and closing movement about an end of the shoe to lay the upper over the insole, and a device mounted for advancing movement with said wipers in engagement with the bottom of the shoe to determine the position of the wipers relatively to the plane 95 of the shoe bottom.

60. In a machine of the class described, the combination with shoe positioning means, of end embracing wipers mounted for advancing and closing movement about an end of the shoe to lay the margin of the upper over the insole, a support for said wipers movable transversely of the plane of the shoe bottom, and a roll on said support for engaging the bottom of the shoe to determine the position of the wipers relatively to said plane as they close inwardly over the shoe. 100

61. In a machine of the class described, the combination with shoe positioning means, of end embracing wipers mounted for closing movement over the bottom of the shoe and also for movement heightwise of the shoe, and a member mounted for movement with said wipers heightwise of the shoe into position to engage the bottom of the shoe, said member being arranged to determine by engagement with the bottom of the shoe the position of the wipers relatively to the plane of the insole in the closing movement of the wipers over the shoe. 110

62. In a machine of the class described, the combination with shoe positioning means, of lasting devices movable inwardly over the bottom of the shoe and arranged to operate respectively on different portions of the margin of the upper, one of said lasting devices being arranged to control by engagement with the shoe the position of the other lasting device relatively to the plane of the shoe bottom. 125

63. In a machine of the class described, the combination with shoe positioning means, of lasting devices arranged to operate respectively on different portions of the margin of the upper, one of said lasting devices being mounted for upward and inward movement over the edge of the shoe bottom, and the other lasting device being connected to said upwardly and inwardly movable device to be lifted thereby into predetermined relation to the plane of the shoe bottom.
64. In a machine of the class described, the combination with shoe positioning means, of end embracing wipers mounted for advancing and closing movements at opposite sides of an end of the shoe, a wiper support movable to advance the wipers, and a roll on said wiper support movable upwardly and inwardly over the edge of the shoe bottom between the wipers and arranged to lift the wiper support to position the wipers relatively to the plane of the shoe bottom.
65. In a machine of the class described, the combination with shoe positioning means, of overlaying mechanism mounted for movement inwardly over the bottom of the shoe to lay the margin of the upper over the insole, power operated controlling means automatically operative to effect a positioning movement of said overlaying mechanism transversely of the plane of the insole prior to the operation of the overlaying mechanism on the shoe, and means for engaging the bottom of the insole to determine the limit of such positioning movement.
66. In a machine of the class described, the combination with shoe positioning means, of overlaying mechanism mounted for movement inwardly over the bottom of the shoe to lay the margin of the upper over the insole, cam controlled spring means for imparting to said overlaying mechanism a positioning movement transversely of the plane of the insole, and a gage member carried by said overlaying mechanism for engaging the bottom of the shoe to determine the limit of such positioning movement.
67. In a machine of the class described, the combination with means for positioning a shoe bottom upward, of end lasting mechanism mounted for advancing movement lengthwise of the shoe and for positioning movement heightwise of the shoe, a cam for releasing said lasting mechanism to permit it to move downwardly prior to its operation on the shoe, and a member for engaging the bottom of the shoe to limit such downward movement.
68. In a machine of the class described, the combination with means for positioning a shoe bottom upward, of end embracing wipers and a wiper support mounted for advancing movement lengthwise of the shoe and for positioning movement heightwise of the shoe, automatic means for imparting downward positioning movement to said wiper support in time relation to its advancing movement, and means on said wiper support for engaging the bottom of the shoe to limit such downward movement.
69. In a machine of the class described, the combination with means for positioning a shoe bottom upward, of end embracing wipers and a wiper support mounted for advancing movement lengthwise of the shoe and for positioning movement heightwise of the shoe, a cam for releasing said wiper support to permit it to move downward prior to the operation of the wipers on the shoe, and a gage member on said wiper support for engaging the bottom of the shoe to limit such downward movement.

In testimony whereof I have signed my name to this specification.

BERNHARDT JORGENSEN.
